UNITED STATES PATENT OFFICE.

WERTUS G. CURRENT, OF WILLOUGHBY, OHIO, ASSIGNOR TO THE BUCKEYE RUBBER PRODUCTS COMPANY, OF WILLOUGHBY, OHIO, A CORPORATION OF OHIO.

DESIGN FOR A VEHICLE TIRE.

61,336.

Specification for Design.

Patented Aug. 8, 1922.

Application filed November 14, 1921. Serial No. 515,139. Term of patent 7 years.

To all whom it may concern:

Be it known that I, WERTUS G. CURRENT, a citizen of the United States, residing at Willoughby, in the county of Cuyahoga and State of Ohio, have invented a new, original, and ornamental Design for Vehicle Tires, of which the following is a specification, reference being had to the accompanying drawing, forming a part hereof.

Fig. 1 is a perspective view of a portion of a tire together with its base or rim, illustrating my new design; and Fig. 2 is a sectional view of a tire exhibiting my new design.

I claim:

The ornamental design for a vehicle tire as shown.
